US00D749009S

(12) **United States Design Patent**
Akana et al.

(10) **Patent No.:** US D749,009 S
(45) **Date of Patent:** ** Feb. 9, 2016

(54) **LINK FOR BAND**

(71) Applicant: **Apple Inc.**, Cupertino, CA (US)

(72) Inventors: **Jody Akana**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Daniel J. Coster**, San Francisco, CA (US); **Danielle De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Marc A. Newson**, London (GB); **Matthew Dean Rohrbach**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Eugene Antony Whang**, San Francisco, CA (US); **Rico Zörkendörfer**, San Francisco, CA (US)

(73) Assignee: **Apple Inc.**, Cupertino, CA (US)

(**) Term: **14 Years**

(21) Appl. No.: **29/501,760**

(22) Filed: **Sep. 8, 2014**

(51) LOC (10) Cl. **11-01**

(52) U.S. Cl.

USPC **D11/94**

(58) **Field of Classification Search**

USPC D11/1-25, 32, 93, 94; 59/78, 79.2; 63/1.11, 3, 3.1, 3.2, 5.1, 5.2, 7-11; 224/175; D10/30-32

CPC A44C 5/02-5/246

(57)

CLAIM

The ornamental design for a link for band, as shown and described.

DESCRIPTION

FIG. 1 is a front perspective view of a link for band showing our new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

1 Claim, 3 Drawing Sheets
